Fig. 1

Fig. 2

Fig. 3

FIG. 1 is a perspective view of a tire embodying our new design, it being understood that the full line portion is repeated throughout the circumference of the tire, shown by means of broken lines;

FIG. 2 is an enlarged fragmentary plan view of the full line portion shown in FIG. 1;

FIG. 3 is a sectional view taken substantially on the plane indicated by line III—III of FIG. 2, but on a reduced scale.

The dominant features of our design reside in those portions shown in full lines in the drawings.

We claim:

The ornamental design for a tire, substantially as shown and described.
